UNITED STATES PATENT OFFICE.

HARRY A. CUMFER, OF CHICAGO, ILLINOIS, ASSIGNOR, BY MESNE ASSIGNMENTS, OF ONE-HALF TO THE FLINTKOTE COMPANY, OF BOSTON, MASSACHUSETTS, A CORPORATION OF MASSACHUSETTS.

ROOFING PRODUCT.

Application filed August 9, 1919. Serial No. 316,374.

To all whom it may concern:

Be it known that I, HARRY A. CUMFER, a citizen of the United States, residing in the city of Chicago, county of Cook, and State of Illinois, have invented certain new and useful Improvements in Roofing Products, of which the following is a specification.

My invention relates to an improved roofing product, and has for its object to produce embossed paper or felt roofing material which has been saturated or impregnated with asphaltum or other bituminous substance and which may or may not have a granular surfacing. It also concerns the hollow pocket beneath the embossed part which may be filled to make the lower side of the roofing a smooth surface. Another feature of my invention is the mode of laying the roofing strips.

Another important object of the invention is to provide an embossed roofing material which has the appearance of shingles, tile or the like and furnishes a mode of laying these roofing strips which is less difficult than the flat roofing strips and can be more permanently affixed due to the lower edge of the strips abutting the upper shoulders of the embossed portions of the strips below, making a more unified combination or assembly.

The roofing herein disclosed consists of pliable units cut from a sheet in which are impressed or stamped raised portions which have the concave indentures formed on the under side of the sheet filled with an adhesive substance such as asphalt or other bitumens. The hardening of the adhesive substance in the indenture prevents the flattening of the raised portions which appears on the upper surface of the shingle units and assists materially in laying the shingle. The asphalt which is pressed on the surface of the sheet produces a distinct design which may be made to resemble a shingle design of any type. The sheet may be covered with granular surfacing.

Fig. 1 is a plan view of section of roofing as applied.

Fig. 2 is a sectional view on irregular dotted line 2-2 of Fig. 1, looking in direction of the arrows.

Fig. 3 is a plan view of section of roofing shown.

Fig. 4 is a sectional view taken on a broken line similar to that shown in Fig. 1.

Fig. 5 is a detailed view of roofing strip surfaced with granular material.

Fig. 6 is a sectional view along lines 6-6 of Fig. 5, viewed in direction of arrows.

Fig. 1 is a section of laid roofing, the arrangement of the strips being the same as in Fig. 3, except that these strips have not the projections 18 and notches 19 near the top of each strip used to fit them together as shown in Fig. 3. Each strip in both Fig. 1 and Fig. 3 overlaps the one below it and has its lower edge 21 abutting upon the upper shoulders 21^a of the embossed portions 70 4 of the strip below, thus making a very rigid assembly.

In Fig. 5 is an embossed granular, surfaced roofing strip 22. The dark shaded portions 23 are caused by the bosses on the bed roll, forcing the asphaltic substance through the roofing material, giving the top surface on the embossed parts a darker color than the surrounding material.

In Fig. 6, the pocket under the embossed parts of the strip is shown in cross section filled with material 24, (preferably asphaltic) making a smooth under surface on the strip.

The invention is not limited to the details of this particular product except as is pointed out in the appended claims which form a part of this specification.

I claim as my invention:

1. Prepared roofing comprising shingle elements adapted to overlie when placed on a roof, having bossed portions formed in the sheet extending from the lower edge thereof the embossed portions of one element being staggered relative to the embossed portions of the element above and below, the indentures beneath said embossed portions being filled with filler substance.

2. Prepared roofing composed of shingle elements adapted to overlie when placed on a roof, having an adhesive coating and a granular surface upon the coating, bossed portions formed in the sheet showing the coating in distinct markings through the

granular surface to form a design, the lower edge of one element abutting the embossed portion of the element beneath it, the embossed portions being alternately staggered.

5. 3. A roofing element having an adhesive coating and a granular surface upon the coating, embossed portions showing the

coating in distinct markings through the granular surface, and an adhesive substance filling depressions beneath the embossed portions to preserve the shape of the embossed portions and lying substantially flush with the under surface of the roofing.

HARRY A. CUMFER.
